UNITED STATES PATENT OFFICE.

FRANCIS OLSON, OF STORY CITY, IOWA.

OIL BURNER.

1,403,057.

Specification of Letters Patent. Patented Jan. 10, 1922.

Application filed July 26, 1920. Serial No. 398,961.

To all whom it may concern:

Be it known that I, FRANCIS OLSON, a citizen of the United States, of Story City, in the county of Story and State of Iowa, have 5 invented certain new and useful Improvements in Oil Burners; and I do hereby declare the following to be a full, clear, and exact description of the invention, such as will enable others skilled in the art to which 10 it appertains to make and use the same.

My invention relates to oil-burners, and it has for its objects to provide a device of this character adapted to burn either heavy oils, such as petroleum crude oil, or light 15 oils, such as alcohol; one which may be used to burn a mixture of oil, air and steam, air and oil or oil alone; and such a burner in which the oil or oil, air and steam is heated in its passage to the point of ignition.

20 A further object is to provide an improved oil-burner which can be easily cleaned by forcing live steam through the burner and also by movable plungers or needle valves placed opposite the burner jets 25 and operated from the outside, in case the burner should at any time become clogged by reason of using extra heavy oils or for other reasons, and still further objects are to provide an oil-burner in which the flow of oil 30 and steam or oil alone can be regulated automatically by a steam pressure control thereby insuring a steady and uniform heat with resulting economy in fuel; and a burner in which the steam and oil before and after 35 becoming mixed with each other are so highly superheated as to issue from the burner jets in the form of a highly combustible gas.

I have knowledge of oil-burners in which 40 the combination of oil, air and steam are used and in which the oil is heated before being mixed with the steam but my observations of the use of steam lead me to believe that the steam must be dry, superheated steam, 45 as saturated steam will have a tendency to lower the temperature of the flame and produce smoke. I am also aware that some burners have been provided for the superheating of the steam before it is mixed with 50 the oil. However, my burner dries and superheats the steam before it comes in contact with the oil and thereafter the whole mixture is subjected to further heat with the result that if the proper degree of superheating is attained the mixture issues in the 55 form of a highly combustible gas which

burns with a white, intensely hot flame, particularly free from smoke and residue of any kind.

In the drawings, Figure 1 is a view of 60 the burner from the front of the furnace showing the burner base. Figure 2 is an inside end view of the burner with the cap and valve removed. Figure 3 is a sectional view of the burner taken through two of the two 65 or more jets or fuel outlets with which it will be provided.

Referring to the drawings, 1 is a casing which I call the burner head. It is of cylindrical form open at one end. Into and 70 through the closed end is screwed a steam pipe 2. Inside the steam pipe is an oil pipe 3, and within this oil pipe and extending through the burner head is the stem 4 of a valve 5 adapted for automatic operation in 75 a manner to be hereinafter described. 6 indicates the burner jets or fuel outlets of which there may be two or more, depending upon the size of the burner. These burner jets or nozzles may form a part of 80 the casing 1 or they may be separate parts screwed into the openings therein. The burner jets are preferably flared in known manner to secure a twist or spread of the flame. 6' indicates the air intakes which 85 will vary in number according to the number of burner jets or fuel outlets. 7 is a casing or pipe surrounding a generator or mixing tube 14 but which is of less length than the tube. 8 indicates additional air intake 90 space between the casing 7 and a short casing or pipe 9 set in the brickwork of the furnace or in the fire box as the case may be and surrounding the burner proper. Pipe 7 is perforated, as at 13, to admit air 95 to the flame. By closing the oil valve and forcing live steam through a blow out hole 10 the burner may be quickly and effectively cleaned. The generator tube 14, oil and steam pipes are of a diameter to provide 100 ample space for the passage of the oil, steam, and steam and oil.

Within the generator tube 14 and screwed upon the steam pipe 2 is a concave disc 20. See Figure 2. The purpose of this disc is 105 to center the steam pipe 2 within the burner. It is placed slightly below the end of the pipe 2 and thereby forms a cup which when the burner is in a vertical position catches any fuel not immediately gasified. It also 110 causes the newly formed gas to flow close to the hottest part of the generator tube

through the slotted holes or notches 21 in the disc. For centering the oil pipe within the steam pipe 2 I provide a grooved coupling 17. Within oil pipe 3 and threaded to it is a 5 short pipe 19, which is also grooved, centering the valve rod or stem 4 within the oil pipe 3. The grooves of the coupling 17 and the pipe 19 permit the passage of steam and oil.

10 In Figure 3 is shown a cap 16 screwed over the generator tube 14. Against this cap the valve rod 4 abuts in such manner as to prevent the valve 5 from opening or closing more than is desired. The space between the 15 end of the steam pipe 2 and the valve may be regulated by moving the fuel valve 5 either up or down on the valve stem and fastening by means of one or more set screws.

The generator tube 14 may be centered 20 within the casings 7 and 9 by any preferred means such as screws 11 extending through casings 7 and 9. The apertures or perforations 13 in casing 7 admit air drawn in through the openings 8 into the flame chamber. The oil and steam pipes are appropriately connected to sources of supply. The steam pipe 2 has an extension to which is attached a cylinder 30 in such manner that the piston head 25 on valve stem 4 has a slight 25 sliding movement within one end of the cylinder. Within the cylinder is a coil spring 26 one end of which abuts the piston 25 and the other a short rod 28, at the end of which is attached a small hand wheel 27. 29 is a packing gland formed by providing a cap or cylinder head over the cylinder 30. The short rod 28 passing through this cylinder head is threaded in such manner as to permit the rod to be screwed in or out and thereby 30 increasing or decreasing the pressure of spring 26 within the cylinder. It will be seen that the steam pressure of the boiler acting directly against the piston 25 and the valve 5, will, when sufficient to overcome the 35 pressure of the spring 26, force the piston outward and against the spring, thereby partially or completely closing the valve 5 and partially or completely shutting off the fuel. When the steam pressure recedes to a point 40 where the spring overcomes the steam pressure the valve will open to admit additional fuel. By means of the hand wheel 27 the spring can be adjusted so as to operate at any desired steam pressure. In this manner 45 is provided an automatic control over the fuel supply by means of a steam pressure control operated by a rising or lowering steam pressure in the boiler. 24 shows a needle valve set in a packing gland 23, the 50 purpose of which is to provide an easy means of cleaning the nozzles or jets 6 in case they should become clogged.

From the foregoing it will be seen that the oil entering the pipe 3 flows through the pipe 55 into the burner, being heated on the way by

steam in pipe 2. At the automatic valve 5 the oil is atomized by the steam and the resulting mixture is formed into gas within the generator tube 14. Passing back to the burner head the gas is blown through the jets or nozzles 6 with great force, inducing an air draft through the spaces 6' and 8 (Figure 1). The air from space 8 is admitted through holes 13 in casing 7 (Figure 3) thereby mixing thoroughly with the gas. 75 The gas bursts into flame near the end of the casing 9.

While in the foregoing description I have more especially referred to the use of oil and steam as the substance for ignition, it is to 80 be understood that where compressed air is available for commingling with the oil saturation of the air with the oil prior to introduction into the pipe 3 is highly desirable as a medium of economy.

I claim as my invention:

1. An oil burner including an outer cylindrical casing, a second casing within said casing and spaced therefrom, said casings having air intakes at the rear ends, said second casing having a series of apertures, a mixing tube centrally disposed of said second casing and screwed into the rear end of said casing, a steam pipe within said mixing tube, an oil pipe within said steam pipe, each of said pipes extending through the major portion of said mixing tube, a valve for automatically closing the outlet from said steam and oil pipes into said mixing tube, and a series of jet burners formed in the rear end of the mixing tube and having fuel supply connections with said tube. 95

2. An oil burner including an outer cylindrical casing, a second casing within said first casing and spaced therefrom, said casings having air intakes at the rear ends, said second casing having a series of apertures, a mixing tube centrally disposed of said second casing and screwed into the rear end of said casing, said mixing tube extending beyond the inner ends of said casings, a steam pipe within said mixing tube, an oil pipe within said steam pipe, each of said pipes extending through the major portion of said mixing tube, a valve for automatically closing the outlets from said steam and oil pipes into said mixing tube, and a series of jet burners formed in the rear end of the mixing tube and having fuel supply connections with said tube, the flame from said jets surrounding and heating said mixing tube. 105

3. An oil burner including an outer cylindrical casing, a second casing within said first casing and spaced therefrom, said casings having air intakes at the rear ends, said second casing having a series of apertures, a mixing tube centrally disposed of said second casing and screwed into the rear end of said casing, a steam pipe within said mixing tube, an oil pipe within said steam pipe, each 110

- of said pipes extending through the major portion of said mixing tube, a valve for closing the outlet from said steam and oil pipes into said mixing tube, means actuated by steam pressure for controlling the closing movement of said valve, and a series of jet burners formed in the rear end of the mixing tube and having fuel supply connections with said tube.
- 10 4. An oil burner including an outer cylindrical casing a second casing within said first casing and spaced therefrom, said casings having air intakes at the rear ends, said second casing having a series of apertures, a 15 mixing tube centrally disposed of said second casing and screwed into the rear end of said casing, a steam pipe within said mixing tube, an oil pipe within said steam pipe, each of said pipes extending through the major 20 portion of said mixing tube, a valve for closing the outlet from said steam and oil pipes into said mixing tube, spring tension means for normally maintaining said valve in open 25 position, a piston connecting with said valve and actuated by steam pressure for closing said valve against the tension of said spring,
- and a series of jet burners formed in the rear end of the mixing tube and having fuel supply connections with said tube.
5. An oil burner including an outer cylindrical casing, a second casing within said first casing and spaced therefrom, said casing having air intakes at the rear ends, said second casing having a series of apertures, a mixing tube centrally disposed of said second casing and screwed into the rear end of said casing, said mixing tube extending beyond the inner ends of said casings, a steam pipe within said mixing tube, an oil pipe within said steam pipe, each of said pipes 30 extending through the major portion of said mixing tube, a valve for automatically closing the outlet from said steam and oil pipes into said mixing tube, a series of jet burners formed in the rear end of the mixing tube 35 and having fuel supply connections with said tube, the flame from said jets surrounding and heating said mixing tube, and a needle valve for each jet.

In testimony whereof I have signed this 50 specification.

FRANCIS OLSON.
